United States Patent Office

Des. 217,494
Patented May 5, 1970

217,494

LIGHTING FIXTURE

John Dalton, Jr., Wheeling, W. Va., assignor to Sylvania
Electric Products Inc., a corporation of Delaware

Filed Apr. 10, 1967, Ser. No. 6,617

Term of patent 14 years

Int. Cl. D26—02

U.S. Cl. D48—23

FIG. 1

FIG. 2

FIG. 3

FIG. 1 is a perspective view of a lighting fixture showing my new design.

FIG. 2 is a bottom view of the lighting fixture of FIG. 1.

FIG. 3 is an end view of the lighting fixture of FIG. 1.

The lens panel is transparent, the oblique line shading being omitted in FIGS. 1 and 2 for convenience of illustration.

I claim:

The ornamental design for a lighting fixture, as shown and described.
